FIG. 7

FIG. 8

FIG. 9

FIG. 1 is a front perspective view of a portable sewing machine showing our new design in a storage position with the handle in a raised position;

FIG. 2 is a rear perspective view thereof;

FIG. 3 is a front elevational view of the sewing machine with the cover removed and the machine in a position of use;

FIG. 4 is a rear elevational view thereof;

FIG. 5 is a top plan view;

FIG. 6 is a bottom plan view;

FIG. 7 is an end elevational view;

FIG. 8 is an elevational view of the opposite end; and

FIG. 9 is a front perspective view.

We claim:
The ornamental design for a portable sewing machine, as shown.
